UNITED STATES PATENT OFFICE.

GEORGE N. SAEGMULLER, OF WASHINGTON, DISTRICT OF COLUMBIA.

EQUATORIAL MOUNTING.

SPECIFICATION forming part of Letters Patent No. 448,081, dated March 10, 1891.

Application filed November 17, 1890. Serial No. 371,725. (No model.)

To all whom it may concern:

Be it known that I, GEORGE N. SAEGMULLER, a citizen of the United States, residing at Washington, in the District of Columbia, have 5 invented certain new and useful Improvements in Equatorial Mountings; and I do hereby declare the following to be a full, clear, and exact description of the invention, such as will enable others skilled in the art 10 to which it appertains to make and use the same.

My invention has relation generally to the manner of mounting equatorial instruments, and particularly to that part which supports 15 the polar axis outside of the head-stock. In light instruments of this kind it has been customary to support the instrument at this point by a single wheel having a round or arc-shaped periphery, so as to reduce the bearing-surface to the minimum. Such a device 20 would soon be flattened in a very irregular manner by a large instrument and the efficiency of the latter partly, if not wholly, destroyed. A single wheel with a broader bearing-surface would not answer as a substitute 25 for the rounded wheel, for the reason that, while the bearing-face of the collar would be on substantially the same horizontal plane as the top of the wheel, the axis of the collar 30 would be at an angle to the wheel, and consequently that part of the collar having the greatest diameter would be moving faster than that part having the smallest diameter, and thereby causing the parts to cramp the 35 bearing and twist the instrument to a greater or less extent out of the position necessary for accurate observations. To remove all objections of this kind is the object of my invention, and the object is accomplished by 40 providing a series of thin wheels of the same diameter and mounted loosely upon the same shaft placed parallel with the bearing-face of the collar which rests on the wheels as a bearing for said collar.

45 The invention therefore consists of constructions and combinations, all as will here-

inafter be set forth in the specification and pointed out in the claim, reference being had to the accompanying drawing, in which the figure represents an elevation, partly in section, of a head-stock, its supporting-base, and the polar axis.

A represents the head-stock supported in the usual way and having bearings a and a' ; A', the polar axis journaled in bearings a and a' and having the beveled collar a^2 made of steel and secured to or formed integral with the polar axis, and A² friction wheels or rollers arranged in a frame a^3 , which is forced upward by any desired means, such as a 60 spring or screw, the latter being shown in the present instance and marked a^4 . The collar a^2 is so beveled that that portion which contacts with the wheels or rollers A² will be on a horizontal plane, that relation being retained no matter at what inclination the polar axis may be set because of the particular latitude in which the instrument is to be set up or placed.

The wheels or rollers A² are of the same 70 diameter and loose upon the same axle a^5 , so that each will be free to revolve independently of each other, so that when in contact with the beveled face a^6 of the collar each wheel will be free to revolve in accordance 75 with the movement of that part of the beveled face it is in contact with and irrespective of the movement of its adjoining wheel or wheels, which may be two or more.

What I claim as new is—

In an equatorial instrument, the combination of the polar axis having a collar with horizontal bearing-face and a series of wheels or rollers mounted upon a single shaft and supporting the polar axis by contacting with 85 the beveled face of said collar.

In testimony whereof I affix my signature in presence of two witnesses.

GEORGE N. SAEGMULLER.
